UNITED STATES PATENT OFFICE

2,369,952

BACKGROUND NOISE SUPPRESSOR

George F. Devine, Easton, Conn., assignor to General Electric Company, a corporation of New York

Application October 23, 1943, Serial No. 507,409

8 Claims. (Cl. 179—100.4)

My invention relates generally to noise suppression circuits for audio frequency channels of the type in which the appearance of background noise cannot be prevented. It is an object of my invention to provide an improved noise suppression circuit for such channels which operates normally to remove high audio frequency currents only from the output of the channel and which is rendered inoperative by the appearance of high audio frequency currents at the input of the channel to permit translation of such currents by the channel.

In audio frequency translating channels which employ electronic amplifiers, it is customary to employ a noise suppression circuit to reduce noise voltages in the output of the channel in the absence of signals to be translated. The time of operation of such circuits is a factor which enters into their successful application. This time must be long compared to the lowest frequency voltages which it is desired to transmit. In order to avoid distortion of the audio signal being translated, such noise suppression circuits usually operate at syllabic speed. It is an object of my invention to provide an improved noise suppression circuit, the suppressor action of which is limited to higher audio frequencies to permit a very short time constant in the control circuit.

My invention relates more particularly to noise suppression circuits for electric phonograph record reproducers and it has for one of its objects to provide an improved circuit for reducing the record background noise in the output of such a reproducer.

The background noise usually encountered in record reproducers is most annoying during quiet passages of recorded music, when higher frequency tones are not present, and at the beginning and end of records played on automatic record changers, but is not noticed when the recording level is high. Accordingly, it is an object of my invention to provide an improved background noise reducing circuit for record reproducers by which the high frequency response of the reproducer is reduced when higher frequency tones are not present on the part of the record being reproduced or are below the level of the background noise and is returned to normal operation when desirable higher frequency tones, having an intensity greater than that of the background noise, are being reproduced.

Another object of my invention is to provide an improved noise suppression circuit for a record reproducer which has a very short time constant and operates at a rate substantially imperceptible to the human ear.

When a particular type of stylus or pick-up apparatus is employed in an electric phonograph record reproducer, the noise level of both the pick-up apparatus and an average recording may be

determined with a high degree of accuracy. Accordingly, a further object of my invention is to provide an improved background noise reducing circuit for a record reproducer in which a threshold level for disabling of the noise reducing circuit may be set or adjusted above the intensity of the high frequency components of the background noise which it is desired to suppress and below the intensity of high frequency passages on the recording which it is desired to reproduce.

One of the features of my invention is the employment in a noise reducing circuit for an audio frequency translating channel of a low-pass filter which includes an electron discharge device functioning as a reactance device having a predetermined frequency characteristic and varying the reactance of said device in accordance with the intensity of the higher frequency components of the audio signals at the input to said channel.

Another object of my invention is to provide an improved noise reducing circuit for audio amplifiers which includes an electron discharge reactance device having a determinable frequency characteristic.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing, in which Fig. 1 represents a portion of an electric phonograph record reproducer embodying the noise suppression circuit of my invention, and Fig. 2 is a modification of the circuit of Fig. 1. In the two figures corresponding reference numerals have been placed on corresponding elements to facilitate their comparison.

Referring to Fig. 1, I have shown an audio frequency translating channel 10 having an input terminal 11 connected to a source of audio frequency signals and an output terminal 12 supplying audio frequency signals to subsequent stages of the reproducer amplifying circuit and, ultimately, to a suitable sound reproducing device. Connected across the channel 10 between the terminals 11 and 12 is my noise suppression circuit 13.

Audio frequency signals are supplied to the input terminal 11 of the translating channel from a phonograph pick-up device comprising the crystal pick-up 14 connected between the terminal 11 and ground and a crystal loading resistor 15 connected in shunt to the crystal 14 to control the low frequency response of the pick-up device. Connected between terminal 11 and ground is a high-pass filter circuit comprising capacitance 16 and resistance 17. The common point of capacitance 16 and resistance 17 is connected to control

electrode 18 of the triode section of an electron discharge device 19 of the diode-triode type. Anode 20 of the triode section of device 19 is supplied with operating potential through a load resistance 21 from any suitable source of potential, such as the battery 22, and is connected to ground through a capacitor 23 and a resistance 24. The cathode of device 19 is connected to ground for unidirectional currents and low audio frequency currents through resistance 25 and for high audio frequency currents through by-pass capacitor 26. The capacitance of capacitor 26 is small so that only high audio frequency currents, i. e. currents having frequencies above approximately 600 cycles per second, flow readily through capacitor 26. Capacitance 16 similarly is a relatively small capacitance so that the potential of electrode 18 for low frequencies and which is due to the low frequency audio currents flowing through resistance 17 is quite small. Since low audio frequency currents flow from the cathode of device 19 to ground through the high impedance of resistance 25, degeneration occurs and the output current of the triode section of device 19 contains but a small component of audio frequencies below about 600 cycles.

Anode 27 of the diode section of device 19 is connected to the common point of capacitor 23 and resistor 24 and to ground through a filter circuit comprising resistor 28 and capacitor 29.

The audio frequency currents in translating channel 10 flow through a low-pass filter comprising series resistance 30 and electron discharge device 31 functioning as a reactance tube. The anode of device 31 is connected to battery 22 through a load resistance 33 and to the right-hand terminal of resistance 30 through blocking capacitor 34 and capacitor 35 inserted in the filter circuit to enhance the reactive effect of device 31. The device 31 is shown as a pentode having its cathode connected directly to ground and its control electrode 36 connected to the common point of capacitors 34 and 35 and to ground through resistance 37 and capacitor 29. The screen electrode 38 is supplied with operating potential from battery 22 through a voltage dropping resistor 39 and is connected to the cathode through a capacitance 40. The electrode 41 is connected directly to the cathode to act as the usual suppressor grid.

In the operation of the low-pass filter comprising series resistor 30 and the electron discharge device 31, the device 31 functions as a well-known reactance tube having a capacitive reactance which varies with the gain of the tube. In order that the capacitive reactance of the device vary also with the frequency of currents flowing through that device, capacitor 40, connected between screen electrode 38 and the cathode of the device, is made small so that the screen electrode operates practically at ground potential for higher audio frequencies and at potentials considerably above ground for lower audio frequencies. In this manner the device 31 operates as a reactance tube whose reactance varies with the frequency of the currents flowing through the tube. The gain of the device 31 is controlled by the biasing potentials supplied thereto through resistance 37 from the common point of resistance 28 and capacitance 29 in the filter circuit connected between the anode 27 and ground. The value of resistance 37 is made low, in the order of 50,000 ohms, so that this resistance not only functions to prevent reactance device 31 from acting to change noticeably the apparent volume level of the output of channel 10, as device 31 is rendered operative or

inoperative to by-pass high frequency currents from channel 10, but also forms in conjunction with capacitor 34 a tone compensating circuit for the crystal pick-up 14. As stated previously, 5 loading resistor 15 reduces the low frequency response of the crystal pick-up and is commonly found necessary in an electrical phonograph to prevent rumble. The compensating action of tone compensating circuit 34, 37 is limited to the 10 middle frequencies in the output of pick-up 14 and reduces these middle audio frequencies in a degree commensurate with the amount that the lowest frequencies are reduced by resistor 15 so as to produce a pleasing overall tonal quality.

15 In the operation of the complete noise suppressor circuit 13 high audio frequency signals are amplified in the triode section of the device 19 to provide a potential to the anode 27 which is rectified in the diode section of the device 19. 20 Low audio frequencies are prevented from being reproduced in the circuit of anode 20 through the operation of the cathode bias resistor 25 and the high-pass filter circuit 16, 17. The high audio frequency currents are rectified in the diode section of device 19 and filtered by resistance 28 and capacitor 29 to provide a negative bias voltage for control electrode 36 which reduces the gain of device 31 and changes its reactive effect to that of a very small capacity. When the reactance of the device 31 is thus reduced, high audio frequencies in the translating channel 10 are permitted to proceed to the terminal 12 without attenuation.

25 In order to provide a threshold level so that 35 high audio frequency currents, present in the channel 10 and due to surface noise alone in the output of the phonograph record reproducer, cannot reduce the gain of device 31 to permit the high frequency components of this surface noise to pass to the output terminal 12, resistance 25 is made considerably larger than required merely for providing a bias voltage for the triode section of the device 19. In this manner high audio frequency voltages of a predetermined intensity 40 are required to reduce the by-passing effect of device 31. It is apparent, of course, that the flow of current in the diode section of device 19 is delayed also by the voltage developed across resistance 25 so that the gain reducing bias for control electrode 36 is developed only after high frequency audio signals of predetermined intensity are supplied to control electrode 18.

50 When a crystal pick-up of the type shown is employed in an electric phonograph record reproducer, the noise level of the stylus attached to that pick-up device and of the average record can be determined with considerable accuracy. Also, it is well known that the minimum recording level which can be successfully reproduced can be definitely ascertained. Hence, by properly selecting the value of the cathode bias resistance 25, the operating point of the diode section of device 19 may be set or adjusted with sufficient precision that high frequency audio tones are by-passed 65 from the translating channel 10 by the reactance device 31 when the intensity of audio frequency voltages at terminal 11 is below a definite value. In this manner scratchy high frequency background noise present on the recording is not carried to the output circuits of the phonograph record reproducer during quiet passages in the recording, when higher frequency tones are not present, and at the beginning and end of the records being played. When, however, the high frequency notes of the record produce voltages at

terminal 11 above a threshold value, biasing potentials are developed by device 19 to reduce the gain of reactance tube 31 and permit the passing of these high frequency tones to the output circuit of the reproducer.

Since only high frequency currents are rectified by the diode section of device 19, the charging time of capacitor 29 can be relatively short so that negative biasing potential is supplied rapidly to control electrode 36 when desirable high frequency voltages appear at the terminal 11. Thus, the bypassing effect of reactance device 31 is reduced quite rapidly and the switching off and on of high frequency notes in the output circuit of the translating channel occurs at a rate which is substantially imperceptible to the human ear. This control action, while seeming almost instantaneous to the ear, remains relatively slow in relation to the audio frequencies being controlled so that there is no distortion of these audio frequency notes by the control circuit.

In the modification of my invention shown in Fig. 2, the screen electrode 38 of reactance device 31 is by-passed to ground for higher audio frequencies by the capacitor 40 and the cathode of the device is connected to ground through a resistance 45 across which is connected a by-pass capacitor 46. The resistance 45 provides normal bias for device 31 as well as degeneration at the frequencies not by-passed by capacitor 46. Both capacitors 40 and 46 have a capacitance value such that they by-pass only higher audio frequencies. As a result, in this modification of the noise suppressor circuit, the reactance of the reactance tube 31 is increased for higher audio frequencies to be by-passed from channel 10 and has a very small value for low audio frequencies.

The operation of the circuit of Fig. 2 is essentially the same as that of the circuit of Fig. 1. The main difference between the two circuits lies in the fact that low frequency currents flowing through device 31 are reduced to a very small value by the degenerative voltages developed across cathode biasing resistor 45 and the high impedance of capacitors 40 and 46 to these low audio frequency currents. On the other hand, for higher audio frequency currents the cathode and screen electrodes of the device operate practically at ground potential and the gain of the device is controlled by the potential of control electrode 36.

By way of illustration only, and not in any sense by way of limitation, the following representative values are given for a circuit constructed in accordance with Fig. 1 of my invention. A 6SQ7 type of electron discharge device was used as the device 19 with the two diode-anodes of the device being connected together to comprise the anode 27 and a type 6SG7 tube was used as the reactance tube 31. The values of the impedance elements of the circuit are as follows:

Resistance 21=250,000 ohms

Resistance 17=500,000 ohms

Resistances 24, 28, 33=1 megohm

Resistance 39=2 megohms

Resistance 25=10,000 ohms

Resistance 37=50,000 ohms

Resistance 30=100,000 ohms

Capacitor 16=.001 microfarad

Capacitor 26=.1 microfarad

Capacitor 29=.05 microfarad

Capacitors 35, 40=.01 microfarad

Capacitor 34=.00025 microfarad

While I have shown a specific embodiment of my invention, it is apparent that various changes

may be made. Thus, instead of using the bias resistance 25 to obtain a threshold level for the two sections of the device 19, a bias voltage may be used. Similarly, when the audio frequency voltages at the terminal 11 are of high level, or are amplified before passing through the series resistance 30, it is desirable to use a greater bias for both tubes in the device 31. However, in all applications of the noise suppressor circuit, it is desirable that the circuit be applied to stages of an amplifier preceding the volume control means in the amplifier. In this way the circuit remains independent of the output level at which the reproducer is operated and rapid, reliable, and accurate operation of the suppressor circuit is obtained.

While I have shown a particular embodiment of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States, is:

1. In combination, a channel for translating audio frequency signals, means coupled to said channel for attenuating the high audio frequency signals therein while permitting translation of lower audio frequency signals, and means responsive to the presence of intense high audio frequency signals in said channel for reducing the attenuation of said signals by said attenuating means.

2. In combination, a translating channel for audio frequency signals, means coupled to said channel for substantially removing audio signals having a frequency greater than a predetermined frequency from the output of said channel while permitting translation of lower audio frequency signals, means responsive to the appearance of audio signals of a frequency greater than said predetermined frequency in the input to said channel to disable said signal removing means, and means to provide a threshold level for the operation of said disabling means.

3. In combination, a background noise reducing circuit for the audio frequency translating circuit of a record reproducer comprising, a capacitance and a resistance connected in series across said audio circuit, and an electron discharge device connected in shunt to said resistance, said device having a control electrode and said noise reducing circuit being adjusted to remove undesired high frequency currents from said audio circuit, and means to disable said noise reducing circuit to permit translation of desired high frequency currents comprising, means to rectify high frequency voltages present in said audio circuit, and means for applying said rectified voltages to said electrode in a gain reducing sense.

4. In combination, a surface noise reducing circuit for the audio frequency translating circuit of a record reproducer comprising, a capacitance and a resistance connected in series across said audio circuit, and an electron discharge device connected in shunt to said resistance, said device having a control electrode and said noise reducing circuit being adjusted to remove high frequency currents having an intensity less than a predetermined intensity from said audio circuit, and means to disable said noise reducing circuit to permit translation of high frequency currents of an intensity greater

than said predetermined intensity comprising, means to rectify high frequency voltages present in said audio circuit, and means for applying said rectified voltages to said electrode in a gain reducing sense.

5. In a filter circuit for an audio frequency translating channel, the combination of, an input terminal, and an output terminal, an input circuit connected between said input terminal and a point of fixed potential, an output circuit connected between said output terminal and said point, a resistance connected between said terminals, an electron discharge device having an anode connected to a point between said resistance and said output terminal, a cathode connected to said point of fixed potential through a capacitance having a large reactance at low audio frequencies and a small reactance at high audio frequencies, and means to bias said control electrode in accord with the intensity of high audio frequency voltages across said input circuit.

6. In a filter circuit for an audio frequency translating channel, the combination of, an input terminal, and an output terminal, an input circuit connected between said input terminal and a point of fixed potential, an output circuit connected between said output terminal and said point, a resistance connected between said terminals, an electron discharge device having an anode connected to a point between said resistance and said output terminal, a cathode, a screen electrode, and a control electrode, said screen electrode being connected to said point of fixed potential through a capacitance having a large reactance at low audio frequencies and a small reactance at high audio frequencies, means to bias said control electrode in accord with the

intensity of high audio frequency voltages across said input circuit, and degenerative means for low audio frequency currents connected between said cathode and said point of fixed potential.

5 7. In a filter circuit for an audio frequency translating channel, the combination of, an input terminal, and an output terminal, an input circuit connected between said input terminal and a point of fixed potential, an output circuit connected between said output terminal and said point, a resistance connected between said terminals, and a variable reactance connected across said output circuit comprising an electron discharge device having an anode connected to a point between said resistance and said output terminal and a cathode connected to said point of fixed potential, and means to vary the reactance of said device in accordance with the frequency of the current flowing through said device.

20 8. In a filter circuit for an audio frequency translating channel, the combination of, an input terminal, and an output terminal, an input circuit connected between said input terminal and a point of fixed potential, an output circuit connected between said output terminal and said point, a resistance connected between said terminals, a variable reactance connected across said output circuit comprising an electron discharge device having an anode connected to a point between said resistance and said output terminal and a cathode connected to said point of fixed potential, means to vary the reactance of said device in accordance with the frequency of the current flowing through said device, and means to vary the gain of said device in accordance with the frequency of the currents in said input circuit.

than said predetermined intensity comprising, means to rectify high frequency voltages present in said audio circuit, and means for applying said rectified voltages to said electrode in a gain reducing sense.

5. In a filter circuit for an audio frequency translating channel, the combination of, an input terminal, and an output terminal, an input circuit connected between said input terminal and a point of fixed potential, an output circuit connected between said output terminal and said point, a resistance connected between said terminals, an electron discharge device having an anode connected to a point between said resistance and said output terminal, a cathode connected to said point of fixed potential through a capacitance having a large reactance at low audio frequencies and a small reactance at high audio frequencies, and means to bias said control electrode in accord with the intensity of high audio frequency voltages across said input circuit.

6. In a filter circuit for an audio frequency translating channel, the combination of, an input terminal, and an output terminal, an input circuit connected between said input terminal and a point of fixed potential, an output circuit connected between said output terminal and said point, a resistance connected between said terminals, an electron discharge device having an anode connected to a point between said resistance and said output terminal, a cathode, a screen electrode, and a control electrode, said screen electrode being connected to said point of fixed potential through a capacitance having a large reactance at low audio frequencies and a small reactance at high audio frequencies, means to bias said control electrode in accord with the

intensity of high audio frequency voltages across said input circuit, and degenerative means for low audio frequency currents connected between said cathode and said point of fixed potential.

5 7. In a filter circuit for an audio frequency translating channel, the combination of, an input terminal, and an output terminal, an input circuit connected between said input terminal and a point of fixed potential, an output circuit connected between said output terminal and said point, a resistance connected between said terminals, and a variable reactance connected across said output circuit comprising an electron discharge device having an anode connected to a point between said resistance and said output terminal and a cathode connected to said point of fixed potential, and means to vary the reactance of said device in accordance with the frequency of the current flowing through said device.

20 8. In a filter circuit for an audio frequency translating channel, the combination of, an input terminal, and an output terminal, an input circuit connected between said input terminal and a point of fixed potential, an output circuit connected between said output terminal and said point, a resistance connected between said terminals, a variable reactance connected across said output circuit comprising an electron discharge device having an anode connected to a point between said resistance and said output terminal and a cathode connected to said point of fixed potential, means to vary the reactance of said device in accordance with the frequency of the current flowing through said device, and means to vary the gain of said device in accordance with the frequency of the currents in said input circuit.
